UNITED STATES PATENT OFFICE.

NELSON G. GOREAU, OF NEW ORLEANS, LOUISIANA, ASSIGNOR TO GO-RO MANUFACTURING COMPANY, OF NEW ORLEANS, LOUISIANA, A CORPORATION OF LOUISIANA.

FILTER.

No. 918,746.

Specification of Letters Patent.

Patented April 20, 1909.

Application filed February 16, 1907. Serial No. 357,679.

To all whom it may concern:

Be it known that I, NELSON G. GOREAU, a citizen of the United States, residing at New Orleans, in the parish of Orleans and State 5 of Louisiana, have invented a new and useful Filter, of which the following is a specification.

My invention relates to filters, and especially to an economical, simple and durable 10 form of construction for the same, and to cleaning mechanism incorporated in the filter which serves to clean it effectively without dismounting any parts of the apparatus or interfering with the process of filtration.

15 The characteristics and advantages of my invention are hereinafter more particularly set forth in connection with a detailed description of the accompanying drawing which illustrates exemplifying structures in 20 which the invention is embodied, and in which—

Figure 1 is a vertical section; Fig. 2, a detail view of the toggle mounting for the scrapers; and Fig. 3, a detail view of a 25 modified scraper mounting.

Reference numeral 1 designates the bottom plate; 2, the top plate; 3, annular washers or packing carried in annular sockets in the top and bottom plates respectively; 4, the jacket or shell consisting of a cylindrical tube the ends of which rest on the washers 3; 5, a vertical central bolt screwed at its lower end into a socket in the bottom plate; 6, the filter stones of any suitable material which have a central bore and of which the lower one rests upon a washer 7 interposed between it and the bottom plate, and each of the others, which may be of any desired number, rest upon a washer 8 interposed between it and the next lower stone; 9, a collar surrounding bolt 5 near its upper end having a flange 10 bearing upon the upper surface of the upper stone and being formed with a socket 11 containing balls 12; 45 13, a nut engaging a screw-thread 14 on the bolt and bearing upon the collar, and serving when set up to force the collar down upon the top stone and so to lock all the stones firmly together and upon their 50 washers, thus making the stones and bottom plate practically an integral structure; 15, the upper end of bolt 5, preferably of reduced diameter; 16, a screw thread thereon; and 17, a nut engaging thread 16.

After the stones are put in place and 55 locked, the jacket 4 is put in position, the top plate 2 put in place and nut 17 then screwed down serving to firmly lock the bottom plate, top plate, and shell together, and to compress the washers 3, forming a water- 60 tight casing for the entire structure.

18 is a horizontal scraper arm having a hub 19 which is in the form of a sleeve surrounding the bolt, and the lower end of which is formed into a cone running on 65 balls 12.

20 is the upper end of the hub formed into a bearing turning on part 15 of the bolt as a journal; 21, a gear carried by hub 19; 22, a pinion engaging the gear; 23, a shaft carrying the pinion and passing through a stuffing box in the top plate; 24, a crank arm and handle on shaft 23; 25, a vertical scraper arm secured at its upper end to horizontal arm 18; 26, scrapers, preferably one for each 70 stone, although a single scraper may in some cases extend the whole height of all the stones; these scrapers are preferably made trough-shaped as shown in Fig. 2, with two edges 27 bearing against the stone at a 75 proper angle to most effectively scrape off slime or other deposits on the stone, and in some cases disposed at such an angle as to cut off a part of the stone itself if conditions require it. The exact form and arrangement 80 of the scraper may, however, be considerably varied.

40 are toggle arms pivotally mounted on arm 25 at 41; 42, other toggle arms pivoted to arms 40 and mounted pivotally on the 90 scraper at 43; 44, gear teeth formed on the ends of the toggle arms adjacent to each other and serving to make these arms move in unison; and 45, springs serving to extend arms 40, 42.

95 Operation of this mechanism evidently serves to force the scrapers into contact with the stones.

33 are flanges provided on the ends of each scraper, lying against the ends of the corresponding stones and serving as guides for movement of the scrapers, preventing them from riding up and down and wearing or cutting the periphery of the stone unevenly; 100 34, an anti-friction roller carried by the 105 lower end of vertical arm 25 bearing against the shell and serving to take up the thrust of the springs exerted against the lower end of

said arm; 35, a similar roller carried by the horizontal arm 18 near the hub and running on the upper face of flange 10; 36, any suitable supply pipe entering the space exterior 5 to the stone either through the top plate, as shown, or at any other convenient point; 37, the discharge pipe for filtered water communicating with the central bore of the stone; and 38, a discharge pipe for slime and 10 waste created in cleaning the stones, controlled by a valve 39.

In operation, fluid to be filtered enters the casing through supply pipe 36, passes through the stones into the central bore, and 15 out through the discharge pipe 37. Whatever fluid is filtered there is more or less deposit left on the exterior faces of the stones, and this requires to be cleaned off more or less frequently in order that the process may 20 be efficiently continued. To clean the stones in my invention, the crank arm 24 is revolved, turning pinion 22, gear 21, and hub 19, and so revolving horizontal arm 18 and the vertical arm 25 with it around the stones 25 in the space between them and the shell, causing edges 27 of the scraper to remove the deposit and if conditions require it, a part of the stone itself which may have become impregnated with foreign matter. The operation of cleaning is rendered easy by the 30 mounting of hub 19 on ball bearings and the provision of anti-friction rollers 34 and 35; in some cases the ball bearing may be dispensed with, and in this case, anti-friction 35 rollers 35 running on flange 10 serves to keep the parts in alinement, or hub 19 may have a plain bearing upon the cylindrical portion of collar 9. Springs 45 serve to keep the 40 scrapers constantly in contact with the peripheries of the stone and as the latter wear away the particular shape of the springs I employ gives them a wide range of action and enables them to keep the scrapers in proper position even when the stones are 45 worn to very small diameter. It is to be noted that the guide flanges 33, as the stones wear away, keep the lower end of the scraper always in proper relation to the stone and prevent it from moving up and cutting the 50 stone irregularly.

When the cleaning process is going on, valve 39 is open and the waste product passes out through discharge pipe 38 without interfering with the process of filtration except 55 in so far as the reduction in pressure may be effective.

The toggle arms 40, 42, serve to support scrapers 26 rigidly at all times and to keep them properly alined, and at the same time 60 have a very wide range of movement, serving to keep the scrapers firmly in contact with the stones when the latter are new, or very much worn and of small diameter.

In Fig. 3 is shown a modified form of 65 spring mechanism for the scrapers. In

this construction the toggles are dispensed with, and springs 28 having coils 29, are used to connect the scrapers with scraper arm 25. The straight arms of the springs lie against arm 25 and the scrapers for a 70 considerable part of their length, and this braces the springs and enables them to withstand the thrust brought on them in operating the scrapers, without getting out of line. Two sets of springs, such as shown 75 in Fig. 3, are preferably used for each scraper, one near each end thereof.

It is to be understood that I do not limit myself to details herein, but contemplate any changes in the structure which come 80 within the spirit of my invention.

I claim:

1. In a filter, a scraper held in contact with the stones, and having a flange engaging a flat surface of a stone and serving as 85 a guide.

2. In a filter, a scraper having two oppositely-disposed blades in contact with the stones, and a flange engaging a plane surface of the stones and serving as a guide. 90

3. In a filter, a scraper arm, a scraper, and toggle arms connecting the arm and scraper, gear teeth on the arms causing them to move in unison, and springs urging the 95 scraper away from the arm.

4. In a filter, the combination with the stones, of a scraper arm mounted to revolve about the stones, one or more scrapers, means carried by the arm for holding the scrapers against the stones, and flanges on the 100 scrapers engaging the ends of the stones and serving as guides.

5. In a filter, the combination of a scraper arm, a scraper and one or more sets of toggles connecting the arm and the scraper, 105 each set comprising two pairs of toggle arms pivoted to the arm and the scraper, the arms of the pairs being pivoted together oppositely, gear teeth on adjacent ends of the arms of the two pairs of toggles causing them to move in unison, and means urging the toggles to extended position. 110

6. In a filter, the combination with the stones, of a scraper arm revolvably mounted in relation to the stones, one or more 115 scrapers engaging the stones, and toggle mechanism connecting the arm and scrapers.

7. In a filter, the combination with the stones and casing, of a vertical scraper arm mounted revolvably in relation to the stones, 120 one or more scrapers carried by the arm and pressed against the stones, and an anti-friction bearing member carried by the arm and engaging the casing for taking up the thrust of the arm. 125

8. In a filter, the combination of a casing, a base plate, a top plate, a central shaft connecting the plates, a collar secured to the shaft engaging the stones and having a recess, a hub surrounding the shaft, a ball 130

bearing for the hub contained in the recess in the collar, and a horizontal scraper arm carried by the hub.

9. The combination in a filter, of a filtering cylinder, a rotatable body at one end of the cylinder having an arm and a bar extending from the arm and alongside the cylinder; means for rotating the said rotatable body, a scraper movable with the 10 said bar around the cylinder, and a pressure-exerting device arranged between the bar and the scraper and comprising pairs of toggle members; the members of each pair being pivoted together and to the 30 bar and scraper and having gear segments at their outer ends intermeshed with gear segments on the outer ends of the members of the other pair, and springs coiled about the pivotal connections between the members 35 of the pairs and having arms engaging and arranged to move the said members outward.
- 20 10. The combination in a filter, of a filtering cylinder, a rotatable body located at one end of the cylinder and having an arm and a bar extending from the arm and alongside the cylinder, means for rotating 25 the said rotatable body, a scraper movable with the said bar around the cylinder, and

a pressure-exerting device arranged between the bar and the scraper and comprising pairs of toggle members; the members of each pair being pivoted together and to the 30 bar and scraper and having gear segments at their outer ends intermeshed with gear segments on the outer ends of the members of the other pair, and springs coiled about the pivotal connections between the members 35 of the pairs and having arms engaging and arranged to move the said members outward.

11. In a filter, the combination of a casting, a base plate, stones resting on the base 40 plate, a top plate, a central shaft connecting the plates, a collar secured to the shaft and clamping the stones, a hub revolvably mounted on the shaft and a scraper arm carried by the hub.

In testimony whereof I have affixed my signature in the presence of two witnesses.
